UNITED STATES PATENT OFFICE

CHESTER A. RIMMER, OF MALDEN, MASSACHUSETTS, ASSIGNOR TO JACRIM MANUFACTURING COMPANY, OF BOSTON, MASSACHUSETTS, A CORPORATION OF MASSACHUSETTS

DESIGN FOR A TOY POWER BOAT

Application filed November 28, 1930. Serial No. 37,815. Term of patent 7 years.

To all whom it may concern:

Be it known that I, CHESTER A. RIMMER, a citizen of the United States, residing at Malden, in the county of Middlesex and Commonwealth of Massachusetts, have invented a new, original, and ornamental Design for a Toy Power Boat, of which the following is a specification, reference being had to the accompanying drawing, forming a part thereof.

In the accompanying drawing Figure 1 is a view in deck plan, and Fig. 2 is a view in elevation showing my new design, the dominant feature of which is the hull.

I claim:

The ornamental design for a toy power boat, as shown and described.

CHESTER A. RIMMER.
